UNITED STATES PATENT OFFICE.

MALACHI F. BOUGHEN, OF HAMILTON, OHIO, ASSIGNOR TO NILES-BEMENT-POND COMPANY, OF NEW YORK, N. Y., A CORPORATION OF NEW JERSEY.

CAR-WHEEL LATHE.

1,339,017.

Specification of Letters Patent.

Patented May 4, 1920.

Application filed October 10, 1918. Serial No. 257,569.

To all whom it may concern:

Be it known that I, MALACHI F. BOUGHEN, a citizen of the United States, residing at Hamilton, in the county of Butler and State 5 of Ohio, have invented certain new and useful Improvements in Car-Wheel Lathes, of which the following is a specification.

While the invention relates particularly to car wheel lathes, it will be understood that 10 as concerns some of its features it is capable of a broader application. The invention is particularly applicable to car wheel lathes of the type in which the work is driven not only from the headstock end but also from the 15 tailstock end. Inasmuch as the work is driven from both ends the two work-supporting devices are both frequently referred to as headstocks and this term will be used herein. In lathes of this type, one of the 20 headstocks, usually the one at the right, is longitudinally movable along the bed, and the object of the invention is to provide improved means controlled by the movement of the work-supporting device or headstock 25 for stopping the action of the power mechanism when the said device or headstock has been moved to a predetermined position.

The accompanying drawings show the invention applied to a car wheel lathe, but, as 30 stated above, it will be understood that the invention can be otherwise used. The drawings are not to be construed as defining or limiting the scope of the invention, the accompanying claims being relied upon for 35 that purpose.

Of the drawings:

Figure 1 is a front view of one end of a car wheel lathe embodying the invention.

Fig. 2 is a view similar to Fig. 1 showing 40 the controlling mechanism in a different position.

Fig. 3 is a plan view.

Fig. 4 is an end view.

Referring to the drawings, 1 represents 45 the main frame or bed on which many of the other parts are mounted. Longitudinally movable along the bed is a work-supporting device and, in the case of a car wheel lathe, this device is a headstock 2. So far 50 as the present invention is concerned, the construction and mounting of the headstock can be widely varied. As illustrated, however, the head stock comprises a longitudinal spindle 3 mounted in suitable bearings

and a face plate 4 carried by the spindle. 55 At 5 there is a suitable chuck for receiving and holding the axle of the wheels to be turned, this chuck being under the control of a hand wheel 6. A wheel A and part of an axle B are shown in Figs. 1 and 2. 60

For rotating the face plate on the spindle there is provided a large annular gear 7 secured to the face plate. With this gear meshes a pinion 8 on a longitudinal shaft 9 mounted in the headstock frame. Secured to the shaft 9 is a gear 10 which meshes with a gear 11 splined on a longitudinal shaft 12. The gear 11 is positioned between two bearings 13, 13 depending from the headstock, the gear thus being moved longitudinally of the shaft 12 whenever the headstock is moved along the bed. By means of the gearing described, power can be transmitted from the driving shaft 12 to the face plate, the power connection remaining unbroken when the headstock as a whole is moved. 70 75

For moving the headstock along the bed, there is provided a longitudinal threaded shaft or screw 14 which has threaded engagement with a nut 15 secured in the frame of the headstock. The shaft 14 extends through a bearing in a bracket 16 secured to the bed, and is held against longitudinal movement with respect to the bracket. A 80

suitable power device is provided for turning the shaft 14, this power device preferably being an independent electric motor 17. As illustrated, the drive shaft of the motor carries a pinion 18 which meshes with 90 a gear 19 on an intermediate shaft 20. Also carried by the shaft 20 is a pinion 21 which meshes with a gear 22 rotatably mounted on the shaft 14. Also mounted on the shaft 14 is a suitable clutch 23, preferably of the friction type. The driving element of this clutch is secured to the hub of the gear 22 and the driven element is secured to the outer end of the shaft 14. It will be seen that, when the clutch is engaged, power will be transmitted from the motor 17 through the gears 18, 19, 21 and 22 and the clutch 23 to rotate the shaft 14. The shaft 14, by reason of its threaded engagement with the nut 15, serves to move the headstock longitudinally along the bed. The direction of movement of the headstock can be changed by changing the direction of rotation of the 95 100 105

motor by means of a suitable electric controller, which is not shown. The clutch 23 can be engaged or disengaged to start or stop the movement of the headstock by 5 means of a hand lever 24 which is pivoted to the main frame. This lever is connected to the clutch through a link 25 and a lever 26.

After the headstock has been adjusted to the proper position to suitably support the 10 work, it can be clamped in place. Preferably there are two clamping bolts or screws 27, 27 which are adapted to be operated simultaneously. The screws carry arms 28, 28 which are connected by a link 29. One 15 of the screws also carries an arm 30 which is connected by means of a link 31 with a piston in a cylinder 32. By admitting compressed air to the cylinder 32 the piston can be moved, thus turning the screws 27, 27 sufficiently to clamp or release the headstock. 20

When the wheels of one set have been turned and it is desired to remove them, the headstock is withdrawn, being moved toward the right from the operative position 25 to the extreme position shown in Fig. 2. Fig. 1 shows an intermediate position. With machines as heretofore constructed, it has frequently happened that the operator, through negligence, has permitted the 30 power mechanism to continue in operation too long, thus moving the headstock so far as to cause injury or breakage of some part of the machine. In accordance with my present invention I provide means whereby 35 movement of the headstock beyond a predetermined position is automatically prevented, this means being controlled by the headstock movement. As illustrated, there is a lug carried by the headstock which at 40 the proper time engages suitable devices for disengaging the clutch 23, thus stopping the rotation of the shaft 14. Preferably the devices for automatically disengaging the clutch include the hand lever 24 and 45 other parts already described.

As illustrated, there is provided a rod 33 which is mounted on the bed and which is longitudinally movable. The rod is slotted at 34 and a bolt 35 extends through the 50 slot, thus limiting the longitudinal movement. Secured to this rod is a plate 36 which is positioned to be engaged by a lug 37 on the frame of the headstock. The rod 33 is connectible with the hand lever 24, the 55 connection preferably consisting of a pin 38 carried by the lever and entering a notch 39 in the rod. When the headstock is moved toward the right the lug 37 at the proper point engages the plate 36 and moves the 60 rod 33 toward the right. The pin 38 is engaged by the left-hand end of the notch 39, thus moving the lever 24 toward the right and moving the link 25 and the lever 26 so as to disengage the clutch 23. Fig. 1 shows 65 the hand lever 24 in the position to hold the

clutch 23 engaged and thus cause the movement of the headstock toward the right. Fig. 2 shows the several parts in the positions to which they are moved by the headstock, the clutch 23 being disengaged. 70

In order that the lever 24 may be moved manually out of the position shown in Fig. 2 to reengage the clutch, I provide means whereby the lever may be disconnected from the rod. As illustrated, the left-hand end of the rod is vertically movable, being supported by means of a spring-pressed plunger 40. When it is desired to swing the lever 24 toward the left, the operator presses down on the rod 33, preferably with his foot, thus 75 releasing the lever. With the motor 17 turning in the proper direction, the operator can then start the headstock toward its work-engaging position by releasing the lever 24, as described, and swinging it toward the left to engage the clutch 23. When the lever has been thus swung toward the left, the pin 38 is on top of the rod, the rod being held depressed. 80

In order that the rod 33 may be restored 90 to its left-hand position after the headstock has been moved away from its extreme right-hand position, there is provided a spring-pressed plunger 41 which bears against the right-hand end of the rod. This 95 plunger serves to move the rod toward the left as soon as the movement of the headstock permits. When the rod has been thus moved toward the left, the notch 39 becomes opposite the pin 38 and engagement is again 100 effected, the rod being pushed upward by the plunger 40. The parts are thus restored to the position shown in Fig. 1. It will be seen that the lever 24 can be moved toward the right to stop the headstock movement 105 without interfering with the position of the rod 33.

When the headstock is again moved toward the right to its extreme position, the rod 33 is moved as before by the lug 37, thus 110 moving the lever 24 and disengaging the clutch 23 in the way already described.

What I claim is:

1. The combination of a bed, a work-supporting device movable along the bed, power mechanism for moving the said device, mechanism for starting the movement of the said device by the said power mechanism, and means controlled by the movement of the device for stopping the action of the power mechanism when the said device has been moved in one direction to a predetermined position. 115

2. The combination of a bed, a work-supporting device movable along the bed, power mechanism for moving the said device, mechanism for starting and stopping the movement of the said device by the said power mechanism, and means controlled by the movement of the device for stopping 120

the action of the power mechanism when the said device has been moved in one direction to a predetermined position.

3. In a lathe, the combination of a bed, 5 a headstock including a work driving spindle on the bed, power mechanism for moving the headstock inward or outward along the bed, means carried in part by the bed and operable for driving the spindle 10 when the headstock is in any position, mechanism for starting the movement of the headstock by the power mechanism, and means controlled by the movement of the headstock for stopping the action of the 15 power mechanism when the headstock has been moved outward to a predetermined position.

4. The combination of a bed, a work-supporting device movable along the bed, 20 power mechanism including a friction clutch for moving the said device, mechanism for engaging the clutch to start the movement of the said device, and means controlled by the movement of the said device for disengaging 25 the clutch when the said device has been moved in one direction to a predetermined position.

5. The combination of a bed, a work-supporting device movable along the bed, power 30 mechanism for moving the said device, mechanism for starting the movement of the said device by the said mechanism, a rod extending longitudinally of the bed and connected with the power mechanism, and a lug 35 carried by the said device and adapted to engage the rod to move it and thus stop the action of the power mechanism when the said device has been moved in one direction to a predetermined position.

40 6. The combination of a bed, a work-supporting device movable along the bed, power mechanism for moving the said device, a rod extending longitudinally of the bed and connected with the power mechanism, a lug 45 carried by the said device and adapted to engage the rod to move it and thus stop the action of the power mechanism when the said device has been moved in one direction to a predetermined position, and means supplemental to the rod and operable independently thereof for stopping the movement 50 of the said device by the said power mechanism.

7. The combination of a bed, a work-sup- 55 porting device movable along the bed, power mechanism for moving the said device, means for starting and stopping the movement of the said device by the said power mechanism, and means controlled by 60 the movement of the said device for moving the said starting and stopping means to stop the action of the said power mechanism when the device has been moved in one direction to a predetermined position.

65 8. The combination of a bed, a work-sup-

porting device movable along the bed, power mechanism for moving the said device, a manually movable lever for starting and stopping the movement of the said device by the said mechanism, and means controlled by the movement of the said device for moving the lever to stop the action of the power mechanism when the said device has been moved in one direction to a predetermined position. 75

9. The combination of a bed, a work-sup- 80 porting device movable along the bed, power mechanism for moving the said device, a manually movable lever for starting and stopping the movement of the said device by the said mechanism, a rod extending longitudinally of the bed and engaging the lever, and a lug carried by the said device and adapted to engage the rod and thus move the lever to stop the action of the power mech- 85 anism when the said device has been moved in one direction to a predetermined position.

10. The combination of a bed, a work-sup- 90 porting device movable along the bed, power mechanism for moving the said device, a manually movable lever for starting and stopping the movement of the said device by the said mechanism, a rod extending longitudinally of the bed and engaging the lever, 95 a lug carried by the said device and adapted to engage the rod and thus move the lever to stop the action of the power mechanism when the said device has been moved in one direction to a predetermined position, and means permitting the disengagement of the 100 rod from the lever so that the lever may be moved independently of the rod.

11. The combination of a bed, a work-sup- 105 porting device movable along the bed, power mechanism for moving the said device, a manually movable lever for starting and stopping the movement of the said device by the said mechanism, a rod extending longitudinally of the bed and having a notch 110 adapted to receive a part of the lever, a lug carried by the said device and adapted to engage the rod and thus move the lever to stop the action of the power mechanism when the said device has been moved in one 115 direction to a predetermined position, and a spring tending to engage the lever and the rod at the said notch but permitting their manual disengagement.

12. The combination of a bed, a work-sup- 120 porting device movable along the bed, power mechanism for moving the said device, a manually movable lever for starting and stopping the movement of the said device by the said mechanism, a rod extending lon- 125 gitudinally of the bed and engaging the lever, a lug carried by the said device and adapted to engage the rod and thus move the lever to stop the action of the power mechanism when the said device has been 130

- moved in one direction to a predetermined position, and a spring tending to move the rod in the direction opposite to that in which it is moved by the lug. 15
- 5 13. The combination of a bed, a work-supporting device movable along the bed, power mechanism for moving the said device, a manually movable lever for starting and stopping the movement of the said device 20
- 10 by the said mechanism, a rod extending longitudinally of the bed and having a notch adapted to receive a part of the lever, a lug carried by the said device and adapted to engage the rod and thus move the lever to stop the action of the power mechanism 15 when the said device has been moved in one direction to a predetermined position, a spring tending to engage the lever and the rod at the said notch but permitting their manual disengagement, and a spring tending to move the rod in the direction opposite to that in which it is moved by the lug. 20

In testimony whereof I hereto affix my signature.

MALACHI F. BOUGHEN.
